FRED L. KILLIAN, OF AKRON, OHIO

MACHINE FOR MANUFACTURING THIN RUBBER ARTICLES

Application filed January 27, 1928. Serial No. 249,909.

This invention relates to new and useful improvements in machines for manufacturing thin rubber articles and has particular relation to a machine adapted for use in rolling beads on the open ends of toy balloons, rubber gloves, finger cots and other open ended articles of a similar nature.

Objects of the invention are to provide an automatic bead rolling device of simple construction which may be conveniently operated to roll beads with great rapidity which will be efficient in operation and will economically produce beads of uniform cross section.

15 A further object is to provide a bead rolling device which may be used to simultaneously roll beads on a plurality of forms rotatably mounted on a dipping board without removing the forms from the board and 20 which may be used with the board held in a stationary position.

An additional object is to provide new and improved means for rotating forms while the same are in operative contact with the 25 bead rolling element.

Other objects and aims of the invention will be apparent from the following description and from the scope of protection indicated by the appended claims.

30 The above objects are accomplished by the novel construction, combination and arrangement of parts hereinafter described and illustrated in the accompanying drawings in which I have shown a preferred form of 35 the invention, it being understood that the invention is capable of various adaptations and that changes and modifications may be 40 made or resort had to substitutions which come within the spirit of the invention as set forth in the appended claims.

In the drawings similar characters of reference are employed to designate like parts as the same may be shown in any of the several views and in which:—

45 Figure 1 is a side elevational view of a bead rolling machine constructed in accordance with this invention,

50 Figure 2 is a rear elevational view of same, parts being broken away to more clearly illustrate the invention,

Figure 3 is a horizontal, sectional view taken as indicated by the lines 3—3 of Figure 2.

Figure 4 is a vertical, sectional view taken as indicated by the lines 4—4 of Figure 3.

Proceeding now to a detailed description of the invention with reference to the particular adaptation thereof disclosed in the drawings, the numerals 6 and 7 denote upright supports which form the lateral sides of the machine frame and the numeral 8 denotes a table which is suitably secured to the sides 6 and 7. The sides 6 and 7 are also connected by suitable cross members 9, 10 and 11 as illustrated in Figure 2. Each of the side members 6 and 7 are provided adjacent the upper end thereof with forwardly projecting portions which are indicated by the reference characters 6a and 7a. The horizontal table 8 is secured between said brackets 6a and 7a so as to extend across the forward part of the frame with the rear edge thereof terminating in spaced relation to the rear edge of the frame. The members 6 and 7 are provided at points in close spaced relation to the upper ends thereof with axially aligned bearings in which is rotatably mounted a horizontal shaft 12. A cylindrical bead rolling element 13 is fixedly secured to the shaft 12. While the bead rolling element 13 is preferably in the form of a cylindrical brush, it may be formed of any suitable material. The bead rolling element 13 is positioned in a horizontal plane which is spaced above the plane of the table 8 and in a vertical plane spaced rearwardly therefrom.

The numeral 14 denotes a horizontal shaft which is rotatably mounted in suitable bearings on the side members 6 and 7 and is of sufficient length to project from each side of the machine. The end of the shaft 14 which projects from the side 6 is provided with the gear or drive pulley 15 or other means for connecting the shaft 14 to a source of power. The end of the shaft 14 which projects from the side 7 is provided with a beveled pinion 16, which is keyed or otherwise fixed thereto.

The numeral 17 denotes a bracket which is secured to the side 7 of the machine by means of the bolts 18 or other suitable means. A

vertical shaft 19 is rotatably mounted in suitable bearings in the bracket 17. The shaft 19 is provided on the lower end thereof with a beveled pinion 20 which is operatively meshed 5 with the beveled pinion 16. The shaft 19 is provided on the upper end thereof with a beveled pinion 21 which is operatively meshed with the beveled pinion 22 which is fixedly secured to the outwardly projecting end of 10 the shaft 12.

The numeral 23 denotes a bracket which is provided with depending spaced legs 24 and 25. The spaced legs 24 and 25 are provided with alined bores in which is rotatably received 15 the shaft 14. In the drawings I have shown three of the brackets 23 thus mounted on the shaft 24, but it is to be understood that any number of brackets may be employed. Each bracket 23 is provided with a 20 vertical bore in which is rotatably mounted a shaft 26 which projects upwardly at a point above the table 8 as hereinafter described.

A wheel 27 is fixedly secured to the upper end of each shaft 26. While the wheel 27 may 25 be formed in any suitable manner, it is preferably constructed with a peripheral groove in which is mounted a tire or friction strip 28. Each bracket 23 is provided at a point adjacent the upper end thereof with a rearwardly projecting boss 29 in which is mounted a headed bolt 30. The bolt 30 projects through a suitable opening in the member 9 with the head of the bolt 30 spaced rearwardly from 30 said cross member. A suitable coil spring 31 is positioned between the cross member and the head of the bolt. A similar spring 32 is mounted on the bolt 30 for compression between the boss 29 and the cross member 9. Each shaft 26 terminates in spaced relation 35 to the shaft 14 and each shaft 26 is provided on the lower end thereof with the beveled pinion 33 which is meshed with the beveled pinion 34, which is fixedly secured to the shaft 14.

The numeral 35 denotes a board on which is rotatably mounted suitable forms 36. The board 35 disclosed in the drawings is enlarged to hold the forms during the dipping operation and the various other steps of 40 manufacture and is provided with a double row of upstanding pins 37 which are secured in the board 35 in a double row extending longitudinally thereof. Each form 36 is provided with an axial bore 38 in which is received the pins 37. Each form 36 is provided adjacent the lower end thereof with a circumferentially extending groove 39. A strip 40 is positioned between the row of forms with the opposite edges thereof entered in the grooves 39. The strip 40 is suitably secured to the board 35 so that the forms may be retained on the board 35 and may be freely rotated on the pins 37.

In the drawings, I have shown a board 35 45 of ordinary construction having a double

row of forms rotatably mounted thereon, but it is to be understood that any form of supporting member may be used. The form board 35 shown is adapted to be used either singly or collectively in a bed; used to dip 70 said forms in a rubber solution and may be used to carry the forms through the various steps of manufacture.

In use, the gear 15 is operatively connected to a source of power, thus rotating the brush 13 and rotating each wheel 27. A form board 35 carrying the forms 36 on which has been formed the unvulcanized rubber articles 41 is placed on the table 8 so as to be positioned longitudinally thereof. The board 35 is then moved laterally to bring the tire 28 on each wheel 27 into frictional contact with two of the forms 36. The forms 36 being thus frictionally engaged by the rotating members 27 are rotated. A further 80 rearward movement of the board 35 causes a compression of the spring 32 and brings the lower edge of the article 41 into operative engagement with the brush 13. As the forms are rapidly rotating the brush will 85 engage and roll the lower edge of the article 41 upwardly to form a bead of cylindrical cross section. The rapid rotation of the forms causes only a small portion of the article 41 to be rolled upwardly at each rotation of the form 36 and insures an even bead 90 free from lops or knots.

In the particular adaptation of the invention shown, the brush 13 is mounted horizontally whereby each form in the row is simultaneously subjected to the brush thereby forming means whereby beads of uniform cross section can be rapidly and accurately rolled on a plurality of thin rubber articles without removing the forms from the dipping board and without removing the articles 100 from the forms.

In using the boards 35 which carry a double row of forms 36 the forms on one side of the board are first presented to the bead 110 rolling means, the board is then reversed and the forms on the other side thereof are likewise presented to the brush. As both the forms 36 and the brush 13 are being rapidly rotated and as the board 35 is held 115 in a stationary position during the action of the bead rolling means, the beads are very rapidly formed and the board must be held in a stationary position for a very short period of time.

While specific bead rolling means for form rotating means are herein shown and described, it is to be understood that any suitable means may be employed which will function as herein described and claimed.

Having thus fully described the invention with reference to the particular adaptation thereof disclosed in the drawings what is claimed as new and patentable is:

1. In apparatus for manufacturing thin 130

rubber articles, a frame, a cylindrical brush mounted on said frame, means rotating said brush, a form supporting member, forms rotatably mounted in a straight row on said member, friction wheels mounted on said frame for rotating said forms, means to rotate said wheels, said wheels positioned to simultaneously rotate said forms when the same are brought into contact with said brush.

2. In apparatus for rolling beads on thin rubber articles, a support, a cylindrical brush, form rotating wheels, means to simultaneously rotate said wheels and brush, a form carrying member, forms rotatably mounted in a straight row on said member, said forms adapted to be simultaneously brought into operative contact with said brush and wheels when said form carrying member is positioned on said support and moved laterally thereto.

In testimony whereof I have hereunto set my hand.

FRED L. KILLIAN.
